(57) **CLAIM**

The ornamental design for sample tube rack, as shown and described.

DESCRIPTION

FIG. 1 is a perspective view of sample tube rack showing my new design;

FIG. 2 is a front elevational view;

FIG. 3 is a rear side elevational view;

FIG. 4 is a right elevational view;

FIG. 5 is a left side elevational view;

FIG. 6 is a top plan view;

FIG. 7 is a bottom plan view; and,

FIG. 8 is an exploded view.

The broken lines in the drawings depict parts of the sample tube rack that form no part of the claimed design.

1 Claim, 8 Drawing Sheets
